Attorneys.

UNITED STATES PATENT OFFICE.

WILLIAM G. WHITE, OF VESTA, WASHINGTON.

LOG BUNK.

Application filed March 31, 1925. Serial No. 19,668.

My invention relates to log bunks of the general type shown and described in United States Letters Patent No. 1,424,330, granted to me under date of August 1, 1922, and has 5 for its object, in part, changes in the device shown therein whereby the mechanism, the mode of assembling and operating the parts thereof, and accessibility of said parts for the purpose of renewal and repairs are improved.

Besides those features, by way of improvement of my former device, my present invention also comprehends certain new departures in log bunk construction and operative mechanism for log bunks which have utility and applicability in the art independently of my former invention.

What constitutes my present invention will be hereinafter described in detail and succinctly defined in the appended claims.

In the accompanying drawings,

Figure I is a side elevation, partly broken away, with one chock raised and the other depressed, of my present invention in one form of embodiment complete.

Figure II is a bottom plan view of the subject matter of Figure I, showing the relations of parts in their respective log-supporting positions.

Figure III is a view similar to Figure II but illustrating the parts shown therein in their log-releasing positions.

Figure IV is an end elevation of Figure I looking from right to left.

Figure V is an end elevation of Figure I looking from left to right, but with the chock depressed instead of raised.

Figure VI is a top plan view of my bunk having operating mechanism slightly modified from that shown in the preceding figures.

Figure VII is a side elevation as in Figure I of the subject matter of Figure VI showing at the left one chock in the elevated or log-holding position, and at the right the other chock in the depressed or log-releasing position.

Figure VIII is a bottom plan view of the subject matter of Figure VII.

Figure IX is an end elevation of Figure VII, looking from left to right.

Figure X is a side elevation of one end of

my bunk frame, showing the empty half-bearings for the respective journals of a chock and chock supporter exposed by removal of the detachable bearing plate which, 55 in use, holds the journals in place.

Figure XI is an inside elevation of one of the detachable bearing plates, detached.

Figure XII is a vertical cross-section of the bunk frame in preferred form of construction.

Referring to the numerals on the drawings, 1 indicates a bunk frame which is distinctively new and applicable to various different types of bunks. It extends from end 65 of each bunk and includes a hollow arch 2, which extends from one chock to the other, and which is supported at intervals with over-arched ribs 3. The said construction is preferred for the purpose of strengthening 70 the structure of the arch 2 which is surrounded by a longitudinally disposed spine 4.

At the opposite ends of the arch 2, I provide boxes, between the side plates 5 and 6 whereof fit snugly but loosely, chocks 7 and 75 chock-supporters 8. Each chock consists, preferably, of an elongated plate provided at one end with a journal 10 whose ends extend upon opposite sides of the plate as a means for movably supporting the chocks in 80 bearings in the side-plates 5 and 6 of the frame 1.

On its lower side, each chock-plate as above described is provided with a leg 11 which is preferably united to the said plate 85 in an acute angle. The top of each chock-plate is preferably provided with a projection 12 which is disposed in alignment with the spine 4 so as to constitute, in effect a terminal extension thereof whenever the 90 chock is elevated, as shown for instance in Figures I and VII.

Each chock-supporter 8 preferably like the chock consists of a supporting plate and its journals 15, extending therefrom on opposite sides. The plates of each pair of chocks and of the chock-supporters, when in assemblage, extend from their respective journals in opposite directions, as clearly illustrated, for example, in Figure VII, so 100 that when the plate of the supporter 8 is held in horizontal position, as shown at the

left of said figure, as by means hereinafter described, it, in turn, through its engagement with the leg 11, maintains the chock 7 in the log-supporting position.

5 The journals 10 and 15, respectively, are carried at each end of the bunk frame in cylindrical bearings 17 and 18 formed in a side plate 5 on one side of the bunk frame, and on the other side thereof in half-bearings 19 and 20 in the plate 6 opposite to said plate 5, so that either of said journals and parts appurtenant to it may be easily displaced and replaced simply by manipulation whenever occasion may require.

15 Each side plate 6 is completed by a detachable bearing-plate 23 (Figure XI), which is provided with cylindrical bearings 24 and 25 that register, respectively, with the half bearings 19 and 20 in it, and which are also 20 aligned with the bearings 17 and 18 in the companion side-plate 5, whenever the bearing plate 23 is properly positioned on its side plate 6. A shelf rib 25' on the outside of the plate 6 affords a seat for positioning thereupon the bearing plate 23, which when 25 in place is secured to its side plate 6, as by means of screw bolts 26. Inwardly extending bearing cap lugs 27 and 28 on the respective plates 23 fit into recesses 30 and 31 provided for their reception, respectively, in the side-plates 6. When a bearing plate 23 is secured to the side plate 6, substantially as just specified, it serves to fasten the journals 10 and 15 in place, and, by means of 30 the lugs 27 and 28, to effect a retentive covering for them, protecting them where otherwise they would be exposed in the half-bearings 19 and 20.

40 Each of the journals 15 preferably extends beyond the outside face of its bearing members in a squared or flattened terminal 32, which is provided for the reception of a close fitting correspondingly shaped collar 33 and which may be secured to the terminal 45 as by a cotter key 35 inserted into registering apertures provided for it in said terminal and collar, respectively. The collar 33 is provided with an outwardly extended arm 36, whereby the journal 15 may be rocked 50 by hand, for raising and lowering the plate constituting the chock-supporter 8 upon its journals, as often as may be desired.

55 Next, in the order adopted, comes description of supporting and tripping mechanism for operating the chocks 7.

60 In that regard, a broader feature of my invention consists in the shape of the frame 1, whereby provision may be made for enclosing entirely within said frame the mechanism for operating the log-supporting members of the bunk, namely, the chocks 7 for example. Such mechanism comprises essentially any suitable means, available at the will of the operator, for maintaining the 65 members 8 in chock-supporting position or

for tripping them, one at a time, so as to release, according to selection, one of the chocks 7.

In the form of such mechanism by me at present preferred for various reasons, but 70 mainly for its effective simplicity, as well as for the accessibility and adjustability of its parts, I employ a rolling carrier 37 on an axle 38, that is supported at its opposite ends preferably by heavy rollers 39 which travel 75 with loosely snug fit in ways provided for their accommodation in the opposing inner faces of the side pieces 5 and 6 of the frame 1. Said ways may be defined below by supporting tracks 40 and above by overhanging 80 tracks 41 (Figure VII), and are preferably entirely unobstructed at either end, so as to permit introduction of the wheeled axle 38 at either end of the way, and to permit its passage entirely therethrough, if occasion should on any account demand.

85 A coupling 42 bifurcated at its outer end 43, and preferably provided at its inner end with an open ended box connection 44, is provided in its bifurcated end with suitable 90 apertures for reception, in operative accommodation, of the axle 38.

95 To the box connection 44 is detachably fastened at one end, as by a bolt 45, a connecting rod 46, whose opposite end is for purposes of adjustment threaded into the stem 47 of a bifurcated connecting piece 49. The bifurcation of the piece 49 straddles the cross head 50 to one end of which it is pivotally united, as by a pivot bolt 51 (see Figure 1). The other end of the cross head 50 is pivoted upon a stud bolt 52 which projects upwardly from one of a series of cross-bars 53 by which, at proper intervals, the base 105 of the arch 2 is spanned, and which are preferably made flush with the bottom of base flanges 55 that are preferably provided on the opposite sides of the arch. To render each stud bolt 52 easily accessible to a wrench introduced from the outside, I prefer to provide an aperture 56 through the wall of the arch 2 in operative proximity to the two stud bolts, respectively.

110 Between the pivot members 51 and 52, and at a point substantially equidistant from each, is provided a lever-arm 57, disposed say at right angles to the cross head 50, and extending therefrom, in opposite directions, towards the respective ends of the frame 1.

115 The free end 58 of the lever-arm 57 which is preferably slightly deflected into substantially parallel relationship to the longitudinal axis of the frame 1, extends across the top 120 of a terminal one of the four cross-bars 53, which is preferably notched as indicated at 59 to receive and hold it. In operative relationship to the notch 59 I provide a keeper 125 for effectively locking the end 58 of the lever-arm in the notch, and preventing its unintended release therefrom. The keeper 130

may be one of any of suitable kinds, of which two are illustrated. One is a lever pivoted as indicated at 60 to the cross bar last named. Said lever is provided at one end with a counter-weight 61, and at the opposite end with a latch-notch 62.

The other form of keeper shown is a curved latch 63 pivoted to the appropriate side plate 6 as indicated at 64. The free end 10 of the latch 63 serves by its weight to confine therein the end 58 of lever-arm 57.

In Figures VI to IX, inclusive, I illustrate a modified form of mechanism for actuating the respective axles 38. In those figures the preferred details of construction of the rod 46 and its connections are omitted, and the rod, designated therein by a distinctive reference numeral 65, is shown as integral with a connecting piece 66, corresponding to connecting piece 49. One end of the rod 65 is pivotally united, as indicated at 68 to one arm 69 of a bell-crank lever which is pivoted at its elbow 70 to a suitable support located on the outside 20 of the frame 1, so as to present conveniently to the hand of an operator the other lever-arm 71 as a handle for manipulation.

A keeper 72 is provided on the frame 1 in operative proximity to the free end of the lever-arm 71, with substantially the same effect as that described in reference to the latch 63, although by a slightly different method of operation which will be obvious from the drawing alone without further description.

Brief description of the operation of my device is, in view of the foregoing, deemed to be all that is necessary. For setting up the chocks 7 from the depressed position, 40 in which they lie substantially flush with the top of their adjacent side-plates 5 and 6, manipulation of the chocks and of the chock-supporters 8 through the lever 36 on the collar 33 is necessary in order to bring 45 the plate of the member 8 to a substantially horizontal supporting position under the leg 11 of the chock.

Then, by moving one of the axles 38 towards the outer end of the frame 1 that is nearer the said axle, support for one of the chocks is obtained, and, by locking the end 58 of the proper lever-arm in place, the said chock is set up and in so far made ready for loading logs upon the bunk. When 55 both chocks of each bunk are set up, the bunk is ready to receive its load.

For the purpose of unloading, the operator stands at the end of the bunk remote from its discharge end, and after unlocking the lever end 58 from that end of the bunk at which he stands, he withdraws the axle 38 from underneath the plate of the chock-supporter 8 at the remote or discharge end of the bunk. He is thereby enabled to release the bunk load easily, and without en-

dangering himself in respect to life or limb.

What I claim is:

1. In a log bunk, the combination within an oblong hollow frame, of a pair of terminally disposed pivoted chocks hung horizontally therein, and each extending in one direction from its pivotal support, said frame being transversely arched between the chocks, chock supporters also pivoted in the frame and extending oppositely into operative connection with the chocks respectively, and means operatively mounted on the opposite inner walls of the frame for actuating at will either chock supporter.

2. In a log bunk, the combination within an oblong hollow frame, of a pivoted chock hung horizontally therein, and, extending in one direction from its pivotal support, a chock supporter also pivoted in the frame and extending oppositely into operative connection with the chock, and means operatively mounted on the opposite inner walls of the frame for actuating at will the chock supporter, said means comprising a rolling carrier slidably supported by the frame below and in operative relationship to the chock supporter.

3. In a log bunk, the combination within an oblong hollow frame, of a pivoted chock hung horizontally therein, and, extending in one direction from its pivotal support, a chock supporter also pivoted in the frame and extending oppositely into operative connection with the chock, and means for actuating at will the chock supporter, said means comprising a rolling carrier slidably supported by the frame below and in operative relationship to the chock supporter, said rolling carrier working on an axle whose opposite ends travel in ways defined in the 100 opposite inner sides of the frame.

4. In a log bunk, the combination within an oblong hollow frame, of a pivoted chock hung horizontally therein, and, extending in one direction from its pivotal support, a chock supporter also pivoted in the frame and extending oppositely into operative connection with the chock, and means for actuating at will the chock supporter, said means comprising a rolling carrier slidably supported by the frame below and in operative relationship to the chock supporter, said rolling carrier working on an axle whose opposite ends travel in terminally unobstructed 115 ways defined in opposite sides of the frame.

5. In a log bunk, the combination within an oblong hollow frame, of a pivoted chock provided, intermediate of its extremities, with a pendant fixed leg and being hung horizontally therein and extending in one direction from its pivotal support, a chock supporter also pivoted in the frame and extending oppositely into operative connection with the chock, and means operatively mounted on the opposite inner walls of the 125 130

frame for actuating at will the chock supporter.

6. As a part of a log bunk, a transversely arched hollow bunk frame provided with a longitudinally disposed spine in the crown of the arch protruding above and beneath said crown.

7. As a part of a log bunk, a transversely arched oblong hollow bunk frame provided with a longitudinally disposed spine protruding above and beneath the crown of the arch of said frame, and transverse ribs formed on the inner walls of the frame joining and supporting said spine.

8. In a log bunk, the combination with an oblong hollow frame, of a pivoted chock hung horizontally therein, and, extending in one direction from its pivotal support, a chock supporter also pivoted in the frame and extending oppositely into operative connection with the chock, means at opposite ends of the frame for actuating the chock supporters, respectively, located at the end of the frame remote from said means, and

additional means disposed adjacent to the chock supporters, for actuating them, respectively.

9. In a log bunk, the combination with the end of its frame, of opposite frame side-plates provided, respectively, with bearings for pivotal support of a pivoted chock, one of said bearings being open, and an apertured bearing plate securable to the side of the side-plate which has the open bearing, for completing, in effect, said open bearing.

10. In a log bunk, the combination with the end of its frame, of opposite side-plates provided, respectively, with bearings for pivotal support of a pivoted chock, and bearings for a chock supporter adjacent to said bearings, one of said adjacent bearings being open, and an apertured bearing-plate securable to the side of the side-plate which has the open adjacent bearings, for completing, in effect, said open bearings.

In testimony whereof, I have hereunto set my hand.

WILLIAM G. WHITE.
